ATTORNEY

UNITED STATES PATENT OFFICE.

OTIS F. WOOD, OF WEST NEW BRIGHTON, NEW YORK.

DESIGN FOR A SIGN.

SPECIFICATION forming part of Design No. 26,080, dated September 22, 1896.

Application filed June 12, 1896. Serial No. 595,374. Term of patent 3½ years.

To all whom it may concern:

Be it known that I, OTIS F. WOOD, a citizen of the United States, and a resident of West New Brighton, in the county of Richmond and State of New York, have invented and produced a new, useful, and original shape or configuration of an article of manufacture--to wit, an advertising-sign--of which the following is a specification, reference being had to the accompanying drawing, which is a view of an advertising-sign embodying my design.

The leading feature of my design consists in the outline of a projecting or out-thrust or outstretched hand and arm holding outward toward the spectator from any convenient surface, such as a wall, a newspaper, or other thing to be advertised, and also within said outline the delineation of that part of the sur-

face of said hand, arm, and object which is presented toward the spectator.

In the drawing, C is such a hand; E, the object advertised held forward toward the spectator within the grasp of such hand.

D is the arm, in this instance shown clothed with a sleeve.

A is a cuff.

It is preferable to construct the arm and hand of life size.

What I claim is--

The design for an advertising-sign as herein shown and described.

Dated New York, May 23, 1896.

OTIS F. WOOD.

Witnesses:

FRANCIS WHITE PROSCHER,
THOMAS C. BYRNES.
